AUTOMATIC WATCH CLEANING MACHINE

Otto Schurenberg, New York, N. Y.

Application August 16, 1944, Serial No. 549,757

3 Claims. (Cl. 134—77)

1

This invention relates to new and useful improvements in an automatic watch cleaning machine.

More specifically, the invention proposes a new and improved watch cleaning machine which is characterized by a vertical post mounted on a base and having a top ratchet bushing with downwardly directed teeth, a downwardly adjacent reduced idler neck portion, and a fluted cam portion beneath the neck portion. It is contemplated to provide a collar slidably mounted on the fluted cam portion and having upwardly directed ratchet teeth for engaging said ratchet teeth for causing a partial turn of said collar when said collar is moved upwards. It is proposed to so arrange the parts that said fluted cam portion will cause an additional partial turn of the collar when the collar is moved downwards so as to set the collar in a position ready to be moved upwards again to have said ratchet teeth reengaged and cause an additional partial turn of the collar.

It is proposed to mount a table upon the collar referred to above and to support an electric motor driven porous container unit on said table for selectively engaging a plurality of vessels mounted on the base of the machine and around said vertical post and spaced from each other angular distances equal to the spacing of the ratchet teeth.

The invention proposes a time controlled means for raising and lowering the collar so as to automatically cause the collar to turn in steps so that the porous container will be engaged in rotation in said vessels.

Still further the invention proposes an association of a collector ring unit with said collar for controlling the rotations of the electric motor driven porous container.

The invention also proposes that the several vessels be used for different purposes. It is proposed that there be a starting vessel in which a porous container is normally located. It is contemplated that the next vessel contain cleaning fluid, the next one a rinsing fluid, the following one a drying fluid, and the last one a heater for thoroughly drying the parts.

The various parts of watches to be cleaned are placed in the porous container, and then the machine is set into operation and will automatically thoroughly clean and dry these parts.

Still further the invention proposes the construction of an automatic watch cleaning machine which is efficient in action, simple in construction and which may be manufactured and sold at a reasonable cost.

For further comprehension of the invention, and of the objects and advantages thereof, reference will be had to the following description and accompanying drawings, and to the appended

2

claims in which the various novel features of the invention are more particularly set forth.

In the accompanying drawings forming a material part of this disclosure:

Fig. 1 is a plan view of an automatic watch cleaning machine constructed in accordance with this invention.

Fig. 2 is a side elevational view of the machine shown in Fig. 1.

Fig. 3 is another side elevational view but illustrated with certain of the parts in different positions.

Fig. 4 is a fragmentary enlarged detailed view of a portion of Fig. 2.

Fig. 5 is a fragmentary vertical sectional view of the vertical post of the machine and certain related parts.

Fig. 6 is an enlarged horizontal sectional view taken on the line 6—6 of Fig. 4.

The automatic watch cleaning machine in accordance with this invention includes a base 10. The base 10 is hollow and has its top face formed with recesses of various depths to support articles at different elevations. A vertical post 11 is mounted upon said base 10, and is provided with a top ratchet bushing 12 having five downwardly directed teeth 13. The vertical post 11 is also provided with a reduced idler neck portion 14 downwardly adjacent the top ratchet bushing 12.

The vertical post 11 is mounted upon the base 10 by having its bottom end extended through a boss 15 formed in the base. A horizontal set screw 16 is threadedly mounted through a side portion of the boss 15 and engages the bottom of the vertical post for securely holding it in position. The vertical post 11 is also provided with a fluted cam portion having flutes 17 located immediately beneath the reduced idler neck portion 14. There is one flute 17 for each ratchet tooth 13. Each flute 17 has a rounded top 18 arranged slightly laterally of the ratchet tooth above it.

A collar 19 is slidably and non-rotatively mounted upon the fluted cam portion of the vertical post 11. This collar 19 has upwardly directed ratchet teeth 20 complementary to the ratchet teeth 13. The ratchet teeth 20 are adapted to engage the ratchet teeth 13 when the collar 19 is moved upwards for causing a partial turn of the collar 19 due to the fact that the ratchet teeth 13 are stationary and positioned slightly laterally. The ratchet teeth 13 are formed upon a tubular member or bushing which is engaged upon the top of the post 11 and which is fixedly held in position by a set screw 21. The inside face

55 of the collar 19 is formed with five radially inwardly directed teeth 19a, see Fig. 6, one for each of the flutes 17. The teeth 19a slidably engage the flutes and permit vertical sliding of the collar but act to prevent rotation thereof as long as the teeth 19a are engaged with the flutes 17. How-

ever, the teeth 19^a are of a vertical length less than the length of the reduced neck portion 14, and upon upward movement of the collar 19 and as the ratchet teeth 20 approach the ratchet teeth 13, the bottom ends of the teeth 19^a move clear of the top ends of the flutes 17 and into alignment with the reduced neck portion 14 freeing the collar 19 to turn relative to the vertical post 11. Continued upward movement of the collar 19 will cause the ratchet teeth 20 and 13 to engage each other and rotate the collar 19 a major portion of one-fifth of a revolution. When the collar 19 is then moved downwards its teeth 19^a will engage the rounded tops 18 of the flutes 17, causing a slight additional turn of the collar 19 to complete the one-fifth revolution of the collar 19 and disalign the teeth 13 and 20 conditioning them for interengagement on the next upward movement of the collar for a further one-fifth revolution of the collar.

A collector ring unit 22 is coaxially rotatively mounted upon the bottom portion of the vertical post 11. The collar 19 is fixedly mounted on the top of this collector ring unit 22. The unit 22 consists of tubular member 23 having several external annular collector rings 24, 25, and 26 mounted around its top and central portions. The bottom portion of the member 23 is formed into a tapered section 27. The member 23 rests upon ball bearing 28 which is supported on the collar 29 freely mounted on the bottom of the vertical post 11. A brush post 30 is mounted upon the base 10 to one side of the collector ring unit 22. Brushes 31 and 32 are mounted upon the post 30 and normally engage the collector rings 24 and 25, that is when the collector ring unit is in its bottom position. The collector ring unit 22 may be raised and while it is being raised the brushes 31 and 32 will respectively engage and then disengage from the collector rings 26 and 25. When the collector ring unit 22 is in its fully raised position, the brushes 31 and 32 will not touch any of the collector rings.

A table 33 is fixedly mounted upon and radially projects from the collar 19. An electric motor driven porous container unit is mounted upon the table 33. This unit includes an electric motor 35 fixedly mounted on the table 33 and having its shaft 36 extending downwards. A tubular member 37 is mounted upon the shaft 36. A shell-like member 38 is releasably mounted on the bottom of the member 37 by the stem 39 which will be gripped by the resilient split ring 39^a within the tubular member 37. A porous container 40 is removably mounted upon the shell-like member 38. More specifically, the container 40 is formed with radially outwardly extending pins 41 which releasably engage complementary bayonet slots 42 formed upon the inside face of a depending skirt wall of the shell-like member 38. A rubber disc 33^a is provided at the bottom of table 33.

A plurality of containers 43, 44, 45, 46, and 47 are mounted on the base 10 concentric about the vertical post 11. These containers are spaced from each other angular distances equal to the annular spacing of the ratchet teeth 13. These containers have open tops which are axially located along the circumference of the circle corresponding with the axial position of the porous container 40. The container 43 is known as a starting container. Normally when the machine is not in operation the porous container 40 will be located within the container 43, as hereinafter more fully explained. The container 44 is pro-

vided with cleaning fluid. The container 45 has a rinsing solution, the container 46 has a drying solution and the container 47 is provided with an electric heater 48. In the lowered position of the table 33, the bottom face of the rubber disc 33^a engages and closes the open tops of the containers 44, 45 and 46 as shown in Fig. 2.

When the porous container 40 is lowered by tubular member 37 over the electric heater 48, the porous container 40 will be gripped by a pair of spring fingers 49. These spring fingers retain the porous container 40 in position while the tubular member 37 moves upwardly and disengages the stem 39 of the porous container 40. Further details of this construction will not be given in this specification as the fingers 49 form no part of this invention and are generally known in the art.

The support ring 29 is associated with a time controlled means for raising and lowering the table 33 and the collar 19. This time controlled means includes a pair of links 50 pivotally connected with the support ring 29 and extended upwards and pivotally connected with the fingers of a fork-like lever 51. This lever 51 is pivotally mounted intermediate of its ends by a pintle 52 on a standard 53 on the base 10. The rear end of the lever 51 pivotally supports a link 54 which in turn is pivotally connected eccentrically on a disc 55. This disc 55 is mounted on shaft 56 which engages into a gear box 57. This gear box 57 houses a gear transmission which is connected by a coupling 58 with an electric motor 59 mounted on the base 10.

The shaft 56 is also provided with a second disc 60 on the other end thereof. This disc 60 has a projecting eccentrically mounted pin 61. The pin 61 is cooperative with a lever 62 of an electric switch 63 for opening said switch. This lever 62 is provided with a "closing" branch arm 64 which is engageable by the finger 65 of a clock mechanism 66 for closing switch 63. The switch 63 is connected in an electric circuit 67 which includes a manually controlled main switch 68 mounted on the base 10. One parallel section of the circuit 67 connects with and controls the motor 59. The circuit 67 has another parallel section which connects with the brushes 31 and 32. The central collector ring 25 is connected by a lead 69 with the electric motor 35. The collector rings 24 and 26 are connected with the other line 70 of the electric motor 35.

The vessel 43 is illustrated as being provided with a porous container 40'. When the tubular member 37 is being lowered over stem 39' of the porous container in the starting position, the resilient split ring 39^a grips the stem 39' and holds the porous container 40' out of the vessel 43.

The operation of the automatic watch cleaning machine is as follows:

Assume the porous container unit to be at its starting position, within the vessel 43. The switch 63 has been manually closed. The switch 68 is closed for a short period of time, until the disc 55 makes a 180 degree turn. This will cause the support ring 29 to be indirectly lifted by the lever 51, which in turn will raise the table 33 together with the collar 19 and collector ring unit 22. The porous container 40 may now be filled with the parts of the watch to be cleaned. The switches 63 and 68 are now manually closed and the machine is permitted to operate.

Assume that at this point of operation the support ring 29 has not as yet reached its fully raised

position. Consequently it will now be moved up, and during this interval of time, the ratchet teeth 20 will engage the ratchet teeth 13 causing a partial turn of the collar 19. Then the support ring 29 starts moving downwards which will cause the collar 19, table 33, and collector ring unit 22 to move downwards. The collar 19 strikes the curved top ends 18 of the flutes 17 causing a slight additional turn of the collar so that the collar 19 is now ready to be raised during the next step of the operation of the machine.

As the support ring 29 moves downwards to its bottom position, the electric motor driven porous container unit will engage into the vessel 44. When the brushes 31 and 32 engage the collector rings 25 and 26 the electric motor 35 will have an initial supply of current to start it rotating. When the brushes 31 and 32 engage the collector rings 24 and 25, the motor 35 receives an additional supply of current, and now it is rotating at its normal rate. When the support ring 29 moved down, the disc 60 turned and the pin 61 moved lever 62 to open the switch 63 and stop the electric motor 59. This operation continues, that is motor 35 is turning and motor 59 is off until the time clock 66 times off a certain period of time, for example three minutes, and then the lever 65 will strike the lever 64 to close the switch 63 and energize the electric motor 59. The electric motor 59 now starts driving the discs 55 and 60. Rotation of the disc 55 will cause the lever 51 to again raise the support ring 29 and the parts carried by the ring 29. When the collar 19 reaches its top most position, the ratchet teeth 13 cause a partial turn of the table 33. Then the collar 19 starts moving down and there will be an additional turn due to the collar 19 engaging the top ends 18 of the flutes 17. Now the porous container 40 will be located over the vessel 45. The porous container 40 will next engage into the vessel 45. This is the condition as illustrated in Figs. 1 and 2 of the drawings. When the support ring 29 reaches its bottom position, the pin 61 will strike the lever 62 and pass, and move lever 62 so that the switch 63 is turned off and the clock 66 is free to start another timing period. The discs 55 and 60 will stop when the pin 61 is in the position as illustrated in Fig. 2 in which position the lever 62 was moved and opened switch 63 stopping motor 59.

The operation continues in substantially the same way so that the porous container 40 next engages into the liquid of the vessel 46 and then next into the vessel 47 containing the electric heater 48. The next stop of the machine will place the porous container 40 back into the starting vessel 43, and the cycle of the machine has been completed and the main switch 68 is then manually moved to an "off" position shutting the machine off.

The collector rings 24, and 25 and 26 do not extend 360 degrees around the member 23. They extend lesser distances depending upon design, for example they may be so designed that at the "starting" position of the machine, that is, when the porous vessel 40 is within the vessel 43, the circuit to the electric motor 35 is open. Similarly the rings may be designed so that the motor 35 does not operate with the porous container 40 as in the heater vessel 47.

While I have illustrated and described the preferred embodiments of my invention, it is to be understood that I do not limit myself to the precise constructions herein disclosed and the right is reserved to all changes and modifications com-

ing within the scope of the invention as defined in the appended claims.

Having thus described my invention, what I claim as new, and desire to secure by United States Letters Patent is:

1. In a watch cleaning machine having a base upon which a plurality of containers are rested and arranged in a circle evenly spaced from one another about the center of the base forming stations at which cleaning operations are to take place, a vertical post extending from the base at the center of the circle of containers, a collar vertically slidable on said post, a flat circular table attached at its center to said collar and extended radially therefrom above all of the containers, a rotatively mounted porous container for watch parts depended from a radial point on the bottom face of said table for extension into the containers in rotative positions of said collar and table relative to said vertical post, means for successively raising and lowering said collar and table to extend said porous container into and out of said containers, and means operative during raising of said collar and table for turning said table through a major portion of the distance between adjacent containers and during lowering of said table and collar for turning said table through the remaining portion of the distance between adjacent containers, whereby when said table and collar are raised and lowered the porous container will be moved out of axial alignment with one of said containers and into axial alignment with the next adjacent container, said latter mentioned means comprises downwardly inclined ratchet teeth on the top end of said vertical post and including one tooth for each of the containers, upwardly inclined ratchet teeth on the top of said collar and corresponding in number to the number of downwardly directed ratchet teeth, said teeth having their inclined surfaces extended parallel to each other to be engageable during upward movement of said collar and table and just prior to completion of the upward movement and when said porous container is above one of the containers so that further upward movement will engage said teeth and cause said collar and table to be turned through said major portion of the distance between adjacent containers, said vertical post being formed with a reduced neck portion below said downwardly directed teeth and spaced vertical flutes extending downward from said reduced neck portion to points below the top ends of the containers, said flutes having their top ends opening into said reduced neck portion, cam surfaces formed on the top ends of the material of said vertical post between adjacent flutes and being inclined upward at substantially right angles to the angle of inclination of said teeth formed on the top end of said post, and means on said collar engaging into said flutes preventing rotation of said collar and arranged to move out of the top ends of said flutes into alignment with said reduced neck portion as said teeth approach engagement on upward movement of said collar and table and to ride over said cam surfaces on downward movement of said collar and table to turn said collar and table through the said remaining portion of the distance between adjacent containers.

2. In a watch cleaning machine having a base upon which a plurality of containers are rested and arranged in a circle evenly spaced from one another about the center of the base forming stations at which cleaning operations are to take

place; a vertical post extending from the base at the center of the circle of containers, a collar vertically slideable on said post, a flat circular table attached at its center to said collar and extended radially therefrom above all of the containers, a rotatively mounted porous container for watch parts depended from a radial point on the bottom face of said table for extension into the containers in rotative positions of said collar and table relative to said vertical post, means for successively raising and lowering said collar and table to extend said porous container into and out of said containers, and means operative during raising of said collar and table for turning said table through a major portion of the distance between adjacent containers and during lowering of said table and collar for turning said table through the remaining portion of the distance between adjacent containers, whereby when said table and collar are raised and lowered the porous container will be moved out of axial alignment with one of said containers and into axial alignment with the next adjacent container, said latter-mentioned means comprising downwardly inclined ratchet teeth on the top end of said vertical post and including one tooth for each of the containers, upwardly inclined ratchet teeth on the top of said collar and corresponding in number to the number of downwardly directed ratchet teeth, said teeth having their inclined surfaces extended parallel to each other to be engageable during upward movement of said collar and table and just prior to completion of the upward movement and when said porous container is above one of the containers so that further upward movement will engage said teeth and cause said collar and table to be turned through said major portion of the distance between adjacent containers, said vertical post being formed with a reduced neck portion below said downwardly directed teeth and spaced vertical flutes extending downward from said reduced neck portion to points below the top ends of the containers, said flutes having their top ends opening into said reduced neck portion, cam surfaces formed on the top ends of the material of said vertical post between adjacent flutes and being inclined upward at substantially right angles to the angle of inclination of said teeth formed on the top end of said post, and means on said collar engaging into said flutes preventing rotation of said collar and arranged to move out of the top ends of said flutes into alignment with said reduced neck portion as said teeth approach engagement on upward movement of said collar and table and to ride over said cam surfaces on downward movement of said collar and table to turn said collar and table through the said remaining portion of the distance between adjacent containers, said means on said collar comprising radially inwardly extending teeth formed within said collar.

3. In a watch cleaning machine having a base upon which a plurality of containers are rested and arranged in a circle evenly spaced from one another about the center of the base forming stations at which cleaning operations are to take place, a vertical post extending from the base at the center of the circle of containers, a collar vertically slideable on said post, a flat circular table attached at its center to said collar and extended radially therefrom above all of the containers, a rotatively mounted porous container for watch parts depended from a radial point
